(57) **CLAIM**

The ornamental design for a massage roller, as shown and described.

DESCRIPTION

FIG. 1 is a perspective view of a massage roller showing a first embodiment of my new design.

FIG. 2 is a front elevational view thereof.

FIG. 3 is rear elevational view thereof.

FIG. 4 is a top plan view thereof.

FIG. 5 is a bottom plan view thereof.

FIG. 6 is a right end elevational view thereof.

FIG. 7 is a left end elevational view thereof.

FIG. 8 is a perspective view of a massage roller showing a second embodiment of my new design.

FIG. 9 is a front elevational view thereof.

FIG. 10 is rear elevational view thereof.

FIG. 11 is a top plan view thereof.

FIG. 12 is a bottom plan view thereof.

FIG. 13 is a right end elevational view thereof; and,

FIG. 14 is a left end elevational view thereof.

The use of broken lines in the drawings illustrate environmental structure that forms no part of the claimed design.
